US0D1032670S

(12) **United States Design Patent** (10) **Patent No.:** **US D1,032,670 S**
(45) **Date of Patent:** **** Jun. 25, 2024**

(54) **ICE MOLD**

(71) Applicant: **Dongguan Lipin Silicone Products Co., Ltd.**, Dongguan (CN)

(72) Inventor: **Lichuan Jiang**, Dongguan (CN)

(73) Assignee: **Dongguan Lipin Silicone Products Co., Ltd.**, Dongguan (CN)

(**) Term: **15 Years**

(21) Appl. No.: **29/936,316**

(22) Filed: **Apr. 8, 2024**

(30) **Foreign Application Priority Data**

Mar. 28, 2024 (CN) 202430165173.3

(57) **CLAIM**

The ornamental design for an ice mold, as shown and described.

DESCRIPTION

FIG. 1 is a top perspective view of an ice mold, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 2.

The dash-dot-dash broken lines encircling the enlarged views are for annotative purposes only and form no part of the claim thereof.

1 Claim, 10 Drawing Sheets
